FEED AND CURRENT SUPPLY APPARATUS
FOR CONSUMABLE ELECTRODES AND
METHOD OF OPERATING FURNACES
USING THE SAMERaymond L. Southern, Troy, N. Y., assignor to
Allegheny Ludlum Steel Corporation, Bracken-
ridge, Pa., a corporation of Pennsylvania

Application February 20, 1951, Serial No. 211,887

15 Claims. (Cl. 13—14)

1

This invention relates to apparatus for progressively advancing a consumable metal electrode into an arc melting furnace or crucible and to means for supplying energizing current to such electrode.

In employing a consumable electrode of a metal such as titanium, the electrode is fed into the crucible of an arc-melting furnace and an arc is set up between the tip of the electrode and metal in the furnace to heat the electrode up to a melting temperature. The electrode is thus progressively melted down to form an ingot within the crucible. A metal such as titanium can be pressed into sticks which are somewhat porous. Metal powder or sponge, thus compacted, will still retain some residual impurities, depending upon the particular process by which the metal is separated from its compounds. That is, the metal may contain some residual halides such as chlorine, iodine etc., and some residual reducing material such as hydrogen, potassium, magnesium etc., which if not properly eliminated will tend to contaminate the melt. More volatile impurities such as moisture, oxygen or nitrogen may also be present.

The sticks produced by this pressing method may be somewhat irregular in surface contour; they are relatively frangible and somewhat porous. As a result, considerable difficulty has been encountered in effecting an efficient electric contact with the electrode stick as it is being fed. Further, the feed must be positive, but must be accomplished without damaging the relatively frangible stick.

It has thus been an object of my invention to provide new and improved apparatus for feeding and conducting current to a consumable electrode employed in an arc melting operation;

Another object of my invention has been to provide a relatively simple but practical arrangement for feeding relatively frangible, pressed-out sticks of a metal such as titanium.

A still further object has been to devise an effective arrangement for feeding arc-producing current to a consumable electrode while it is being advanced into a melting crucible or furnace;

These and many other objects of my invention will appear to those skilled in the art from the illustrated embodiments and from the pending claims.

In the drawings, Figure 1 is a vertical sectional view in elevation taken through a complete apparatus assembly constructed in accordance with my invention and as applied to an arc melting furnace or crucible;

Figures 2, 3 and 5 to 7, inclusive, are sectional views taken respectively along the lines II—II,

2

III—III, V—V, VI—VI, and VII—VII of Figure 1;

Figure 3A is a side sectional view in elevation taken along the line IIIA—IIIA of Figure 3;

5 Figure 4 is an enlarged sectional detail taken along the line IV—IV of Figure 3;

Figures 8 and 9 are enlarged sectional details of the current applying apparatus disclosed particularly in Figure 2; Figure 8 is taken at a right angle to Figures 2 and 9;

10 Figures 10 and 11 are enlarged sectional details of a modified form of construction used in applying current to the electrode stick; Figure 10 is taken at a right angle to Figure 11;

15 In carrying out my invention, I employ a rectangular stick 11 of substantially square cross-section, pressed out into a suitable length, for example 20 feet. I have found that a cross-section of two inches square is satisfactory. The

20 stick 11 is positioned in an enclosure that is sealed off from the atmosphere and within which a set of feed rolls and a set of electric contact rolls are operatively positioned. The lower end of the electrode stick extends into an arc-melting crucible or furnace 10 and current of opposite

25 potential is supplied to such furnace to thereby form an arc b with a starting charge of metal or with previously melted metal a to progressively build up a pure metal ingot.

30 The progressive rate of feed of the electrode stick 11 may be automatically controlled by a commercial amplidyne or other suitable device to actuate the feed rolls at a rate depending upon the rate of melting of the stick and as governed by the current consumed by the arc b.

35 Referring particularly to Figure 1, it will be noted that due to space limitations, the view is broken away through the crucible 10, as well as through an upper or stick-carrying enclosure 12.

40 The full length of the stick 11 is sealed off from the atmosphere by the vertically-extending enclosure 12 which may be a pipe or tube of an internal diameter of about 2.87 to 3 inches if a 2 inch square stick 11 is employed (has a diagonal dimension of about 2.82"), so that the stick

45 is guided in its movement and supported by the inner wall of the enclosure 12 (see Figure 6). The enclosure 12 has an annular bottom flange portion 12a and an enclosing portion 12b secured thereto by weld metal w to form an integral construction. The enclosure 12 has a gas inlet 12c to its chamber, the purpose of which will be later explained.

50 A second or stick feeder enclosure 16 has a rectangular bottom flange 16a for securing it to third enclosure 40. A top mounting plate member 15 of the enclosure 16 is positioned beneath the enclosure 12 and carries a pair of feed rolls 22 and 32. It will be noted that the member

15 and the flange 16a are secured to the enclosure 16 by weld metal *w*. The flange 12a of the first or upper enclosure 12 is mounted on the top member 15 of the second enclosure 16 by bolts 13; the joint is sealed off by an annular gasket 14. As shown, the chamber defined by the second enclosure 16 is open to chamber defined by the upper or first enclosure 12. When one stick 11 has been advanced, so that its upper end 11a reaches a position near the bottom of the enclosure 12, a new stick is introduced and its lower end is welded to the upper end of the old stick to form a continuous electrode. For this purpose, the bolts 13 may be removed and the enclosure 12 lifted off the enclosure 16.

A feed roll mounting base member 17 is secured to the top mounting plate member 15 to project downwardly therefrom by bolts 18. As shown particularly in Figures 1, 2 and 3, a pair of transversely spaced-apart vertical support members 19 extend downwardly from the base member 17 and carry bearings 20 for the shaft 21 of a knurled feed roll 22. The feed roll 22 has end flanges 22a which project on either side of the stick 11 to guide it during its movement. The shaft 21 at one end extends through a sealing gland 23 in the enclosure 16 and has a chain sprocket 24 secured on such extending end by a key 21a. The sprocket 24 is driven by a chain 24a through a sprocket 25a mounted on a motor 25 which may, in turn, be controlled in its operation by an amplidyne device 26.

As also shown in Figures 1 to 4, inclusive, the spaced-apart support members 19 are at one end slotted out at 33 to receive sleeve bearings 31 which carry a shaft 30 of a second knurled feed roll 32. The outer contour of the bearings 31 is square (as contrasted to the annular contour of bearings 20), in order to guide them in their sliding movement within the slots 33. The second roll 32 which is mounted in an opposed position with respect to the roll 22, also has a pair of end flanges 32a to guide the stick 11. The full lines of Figure 3 show the roll 32 as an idler or backup roll and the dot and dash lines indicate that it may be a drive roll. In any event, its sleeve bearings 31 are slidably mounted in the slots 33 by adjustable screw-downs. Each screw-down, as shown in these figures, has a clamping piece or face plate 34 which is secured on an end of each support 19 over the slot 33 therein by bolts 34a. A screw-down bolt 35 is adjustably positioned to extend inwardly from the piece or face plate 34 into the slot 33, and has a pin end 35a extending into and slidably carrying a spring supporting washer 36a. A compression spring 36 is mounted over the shank of the washer 36a and over a shank 31b of the bearing 31. The springs 36 yieldably press opposite ends of the shaft 30 of the roll 32 inwardly. Thus, the roll is yieldably held in a contacting relationship with one side of the electrode 11. The screw-down 35 may be moved inwardly and outwardly, after its lock nut 35b has been loosened, to adjust the tension of the spring 36. In this manner, the yieldable engagement of the roll 32 with respect to side of the stick 11 is controlled and a positive feed of the stick 11 is effected without any danger of breaking it.

As shown by the dot and dash lines of Figure 3, the roll 32 may also be driven. If this is desired, a pair of sprockets 27 are mounted adjacent opposite ends of the main shaft 21 and a pair of similar sprockets 28 are mounted on extending end portions of the secondary shaft 30.

Chains 28 mesh with the sprockets 27 and 29 on each side of the assembly. As shown in Figure 3A, to obtain the same direction of feed of the two rollers 22 and 32, I provide an idler sprocket 29a on each end of an idler shaft 29b over which the chains 28 run. The shaft 29b is positioned beneath and to one side of the shaft 30 and is journaled within the support members 19 by bearings 29c. In this manner, the roll 32 still has a yieldably mounted relationship, but may be driven from the primary shaft 21 in a timed relationship with the roll 22.

The third or contact roll enclosure or housing 40 is mounted beneath the second enclosure or housing 16 and its chamber is open thereto and carries sets or opposed pairs of electric contact rolls 55. Inert gas may be introduced to the chamber of the enclosure 40 through the inlet 12c of the upper enclosure 12. An upper annular flange 40a is secured by weld metal *w* and projects from the top of the third enclosure 40 to receive a sealing-in gasket 43 and the bottom flange 16a of the second enclosure. Bolt and nut assemblies 41 extend through the flange 16a, the gasket 43, and the flange 40a to secure the second enclosure 16 in a fluid-sealed-off relationship to the third enclosure 40.

At its lower end, the enclosure 40 has a bottom closure plate or member 44 which is secured thereto by weld metal *w* and serves as a support for a mounting base member 45 of the contact rolls 55. The mounting base member 45 rests on an insulating and heat-resistant separator 46 and is secured to the bottom closure member 44 by bolts 47. The bolts 47 are insulated from the mounting member 45 and the closure member 44 by heat-resistant sleeves 47a. It will thus be apparent that the enclosure 40 is electrically insulated from the current-carrying, mounting base member 45.

The mounting base member 45 has two pairs of oppositely-positioned, semi-circular, bearing-contact bores or sockets 45a. Each socket 45a receives a ball end 51 of each contact roll mounting bracket 50. The ball end 51 of each bracket 50 is removably positioned in one of the sockets bearing 45a by a plate member 48 which is secured thereto by bolts 49. Plate member 48 also has rounded cavities or contact bores therein to receive the ball ends 51 and hold them in position within the bearing-contact sockets 45a.

Each bracket 50, as shown particularly in Figures 1, 3 and 9, has a pair of contact arms 52 extending upwardly therefrom and defining a bifurcated portion within which a contact roll 55 is rotatively mounted by means of its integral shaft 54. As will be noted, current is carried by the arms 52 through the shaft 54 which rotates therein, as well as through endwise contact of the roll 55 with the arms 52. This provides a maximum path for current flow and eliminates sparking and excessive heating. Each contact roll 55 is adapted, as shown, to ride along one side of the four sides of the electrode stick 11 and by reason of its ball and socket mounting, is free to pivot and move transversely in and out with respect to the stick 11. That is, the axial plane of the roll 55 or the transverse plane of the bracket 52 may be pivoted as well as the longitudinal plane of the bracket to move the roll in and out with respect to the surface contour of the stick 11. This is important in view of the somewhat irregular surface presented by the sides of the electrode stick 11; it avoids arcing between the rolls 55 and the stick.

The arms 52 of each bracket 50 (see Figures 1, 2, 8 and 9) have an intermediate offset or groove 52a to receive and position an annular, compression-spring helix 53 to yieldably hold the rolls in surface contact with the sides of the electrode stick 11. That is, the spring 53 is positioned about all four brackets 50 to yieldably hold their rolls 55 in contact and in surface conformance with the sides of the stick 11. Current of one potential (negative) is supplied to the base member 45 by a supply line 57 which is connected to a projecting lug 45b. The line 57 is insulated from the enclosure 40 and a fluid-tight, hermetic seal is provided by an insulating sleeve 56. The parts 45, 48, 50, 54 and 55, are all of a highly conductive metal, such as copper, a copper alloy, or bronze.

The third enclosure 40 is mounted on the furnace of crucible 10 by a fourth, cooling fluid or water-jacketed enclosure 58. The fourth enclosure 58 has an inner metal wall 58a of square design which is spaced from the electrode stick 11, so as to be out of electric contact therewith, see Figure 7. The longitudinal, restrictive, electrode-passageway defined by the wall 58a is connected between the chamber of the enclosure 40 and the crucible 10, see Figure 1. In this manner, a continuous, hermetically-sealed enclosure is provided for the feeding and energizing mechanism of the electrode stick 11.

The fourth or mounting enclosure 58 has a top closure plate 59 which is secured thereto by weld metal w and closes off the upper end of its cooling chamber. The plate 59 is secured to the bottom plate 44 of the enclosure 40 by bolt and nut assemblies 60 whose heads are inset in the member 44, see Figure 1. An annular insulating and heat-resistant gasket 61 seals off the joint between these enclosures from the atmosphere. An annular bottom plate 62 projects outwardly from the enclosure 58 to close off the lower end of its cooling chamber and to provide an end closure for and mount it on the furnace or crucible 10. As will be noted, the enclosure 58 has a cooling fluid inlet 58b and outlet 58c.

The crucible or furnace 10 has a copper flange 10b projecting from its copper inner wall or liner 10a and has a steel flange 9a projecting from its outer steel wall 9. Bolt and nut assemblies 63 extend through the bottom plate 62 of the enclosure 58 and through the flanges 10b and 9a, and are insulated from these parts by a heat-resistant, insulating sleeves 64. Heat-resistant gaskets 65 and 66 seal off and insulate these parts with respect to each other when they are in a secured relationship. It will thus be noted that the enclosure 58 is electrically insulated from the furnace 10 and that metal spatter from the melting operation cannot short circuit the electrode with respect to the furnace. As will be noted, current of opposite potential (positive) is supplied to the flange 10b and thus, to the liner 10a. The fourth or connecting and cooling enclosure 58 is thus insulated from the third enclosure 40.

As shown in Figure 1 of the drawings, the inner wall 10a of the crucible 10 is open to the top of the furnace and has a bottom portion of greater thickness which is removably secured to its side portions by bolt and nut assemblies, so that a formed ingot can be readily removed therefrom after the outer steel wall 9 has been dropped by removing the bolt and nut assemblies 63. Cooling water may be introduced to the walls of the furnace 9 through a bottom outlet and discharged through a top outlet to maintain its inner wall 10a at a proper operating temperature.

A gas that is inert to the metal of the electrode, such as argon, helium, or neon, is introduced through inlet 12c and flows downwardly through the chambers of the enclosures 16, 40 and 58 into the crucible 10 and out through an outlet 8 in the bottom plate 62. In this manner, the more readily volatilizable impurities are swept downwardly at a much faster rate than the advance of the electrode. Impurities are prevented from collecting on the rolls and causing damage to the bearing surfaces. The flow also helps to cool the contact rolls and to prevent appreciable furnace heat from rising into the chamber of the enclosure 40. The inert gas is also employed to flush out the apparatus after the top enclosure 12 has been replaced and vacuum evacuated following the insertion of a new electrode stick. The inert gas will also carry off volatile or gaseous impurities from the crucible 10. The water-jacketing of the enclosure 58 maintains portions of the stick 11 above it at a relatively low temperature, so that the current contact rolls 55 and the feed rolls 22 and 32 are protected from the intense heat of the crucible 10. As shown in Figure 1, the water-cooled, inner wall 58a (a heat baffle) which is positioned closely adjacent to and which has a shape corresponding to that of the electrode 11, thus serves as a heat insulating or segregating means between the relatively hot chamber of the furnace 10 and the chamber of the enclosure 40 which contains the feed and contact roll mechanisms. Thus, the contact roll mechanism 50 may be positioned adjacent the bottom of the enclosure 40 without danger of being damaged by the heat of the furnace.

In Figures 10 and 11, I have shown a slightly modified form of contact roll construction. In this arrangement the bottom base member 45' is mounted in the same manner as the member 45, but has no sockets. Each bracket member 67 has a slightly different form of mounting and is provided with a transverse connector portion 67b. The connector portion 67b is provided with an enlarged slot 67c therein within which a pivot pin or goose neck 68 is loosely positioned. Each pivot pin 68 extends upwardly from a base portion 68a that is secured on the base member 45' by bolts 69. The upper end of the pin 68 is provided with a washer 68b and a cotter pin 68c to somewhat loosely mount the bracket member 67 thereon and permit the desired pivot action thereabout. The construction of the brackets 67 is otherwise substantially the same as the construction of the brackets 50. Each has a groove 67d to receive the compression spring 53. In view of the somewhat loosely mounted relationship of the brackets 67, I additionally provide a braided (flexible) electric connector cable 70 between them and the base portion 68a. This construction also permits the brackets 67 to yieldably move in and out on a transverse plane as well as on a longitudinal plane, so that the rolls 55 will always make a contact of maximum effectiveness with the electrode stick 11.

What I claim is:

1. In melting down a press-formed consumable metal electrode containing readily volatilizable impurities such as halides and reducing material, wherein the electrode is mechanically fed into an electric arc-melting furnace from within a hermetically sealed-off closure positioned above the furnace and having a bottom end connection therewith, wherein electric current is mechanically applied to the electrode within a bottom portion of the enclosure, and wherein electric cur-

rent of opposite potential is applied to metal within the furnace, the method which comprises, establishing and maintaining an electric arc between a lower end portion of the electrode within the furnace and the metal within the furnace, volatilizing the readily volatilizable impurities adjacent a top portion of the furnace, flowing a gas that is inert to the metal of the electrode from the enclosure downwardly along sides of the electrode into the furnace and sweeping the volatilized impurities out of the top portion of the furnace, heat insulating and segregating the atmosphere of the closure from the atmosphere of the furnace while feeding the electrode into the furnace, and effecting the heat insulating by providing an actively-cooled atmosphere about the electrode during its movement from the closure into the furnace.

2. An apparatus for feeding and electrically energizing a consumable metal electrode being introduced into an electrically-energized arc-melting furnace to produce ingots therein which comprises, an enclosure positioned adjacent the furnace and defining a chamber for containing a longitudinal length of the electrode, a second enclosure defining a restrictive electrode-passageway therealong, said second enclosure connecting the chamber of said first-mentioned enclosure to the furnace and defining an end closure portion for the furnace, feeding means positively engaging the electrode to advance it from said first-mentioned enclosure through the passageway of said second enclosure into the furnace, at least a pair of rider contacts operatively positioned within said first-mentioned enclosure to engage the electrode and apply energizing current thereto during its advance into the furnace, said rider contacts having means to yieldably hold them in engagement with the electrode, and said second enclosure being electrically insulated from the furnace to prevent metal spatter from short-circuiting the electrode with respect to the furnace during an arc melting operation therein.

3. An apparatus for feeding and energizing a consumable electrode being introduced into an electric arc melting furnace which comprises, an enclosure positioned on the furnace and defining an electrode-receiving chamber, means connecting the chamber of said enclosure to one end of the furnace, feeding means positively engaging the electrode to advance it into the furnace, at least a pair of electric current-supplying rider contacts operatively positioned within said enclosure to engage the electrode, a positioning part operatively mounting each of said rider contacts for movement transversely of and towards the electrode, and a force-equalizing spring operatively connected between each of said positioning parts to yieldably hold each of said rider contacts in an effective force-equalized electrical contact with the electrode while it is being advanced into the furnace.

4. An apparatus for feeding and energizing a consumable electrode being introduced into an electric arc melting furnace which comprises, an enclosure positioned on the furnace and defining an electrode-receiving chamber, said enclosure having a restrictive electrode-passageway defining means connecting its chamber to the furnace, feeding means positively engaging the electrode to advance it into the furnace, at least a pair of electric current-supplying rider contacts operatively positioned within said enclosure and adjacent the furnace to engage the electrode, a positioning part operatively mounting each of said

75 rider contacts for movement transversely of and towards the electrode, and a spring helix operatively engaging each of said positioning parts to yieldably hold each of said rider contacts in an effective force-equalized electrical contact with the electrode while it is being advanced into the furnace.

5. An apparatus for feeding and electrically energizing a relatively frangible metal electrode of irregular surface contour which is to be introduced into an electric arc melting furnace to produce ingots therein which comprises, an enclosure positioned in a spaced-apart relationship from the furnace and connected at one end thereto, said enclosure being of sufficient length to contain a longitudinal length of the electrode therein, a pair of feed rolls operatively positioned within said enclosure adjacent one end thereof and engaging opposite sides of the electrode, at least one of said rolls being operatively driven to progressively advance the electrode into the furnace, means holding at least one of said feed rolls in yieldable engagement with said electrode to positively advance the electrode without breakage; a set of rider contacts, a positioning member operatively-movably mounting each of said rider contacts within said enclosure between said feed rolls and the furnace, said set of rider contacts having at least a pair of electrically-energized rider contacts engaging opposed sides of the electrode, and a force-equalizing spring operatively positioned about said positioning members and holding each of said rider contacts with an equalized force in yieldable contact with opposite sides of the electrode irrespective of irregularities in the surface contour of the electrode to provide an efficient electrical contact with the electrode at all times without breaking it.

6. An apparatus for feeding and energizing a consumable electrode being introduced into an electric arc melting furnace which comprises, an enclosure above the furnace and defining a chamber, said enclosure being of sufficient length to contain a longitudinal length of the electrode therein, a pair of feed rolls operatively positioned within said enclosure adjacent an upper end portion thereto to engage the electrode and advance it into the furnace, yieldable rider contacts operatively positioned within a lower end portion of said enclosure to engage the electrode and supply electrical current thereto during its advance into the furnace, a heat baffling enclosure connecting the lower end portion of said first-mentioned enclosure to an upper end portion of the furnace and having means to heat insulate said first-mentioned enclosure from the furnace, and said baffling enclosure having an inner wall longitudinally therealong defining an electrode passing chamber that is restricted transversely to provide a minimum clearance between said inner wall and side portions of the electrode during its advance into the furnace.

7. An apparatus as defined in claim 6 wherein, said drive rolls are knurled and have end flanges to guide the electrode, and said rider contacts are positioned in an opposed relationship with respect to each other.

8. An apparatus as defined in claim 6 wherein, a mechanical drive is connected to one of said feed rolls, and the other of said feed rolls is mounted in yieldable engagement with the electrode.

9. An apparatus as defined in claim 6 wherein, a conductive base member is mounted on said enclosure, at least a pair of conductive brackets

are pivotally mounted on said base member, and each conductive bracket of said pair rotatably carries one of said rider contacts.

10. An apparatus as defined in claim 9 wherein, each said bracket carries a ball portion, said conductive base member has a socket thereon to receive said ball portion, and means is secured to said base member to pivotally mount said ball portion within said socket.

11. An apparatus as defined in claim 9 wherein, pivot pins are mounted to project from said base member, and each said bracket is pivotally mounted on one of said pivot pins.

12. An apparatus for feeding and energizing a consumable electrode being introduced into an electric arc melting furnace which comprises, a hermetically sealed-off enclosure positioned to extend above the furnace and defining a chamber, said enclosure being of a sufficient length to contain a longitudinal length of the electrode therein, a pair of feed rolls operatively positioned within said enclosure and engaging the electrode, means positively actuating at least one of said feed rolls to progressively advance the electrode into the furnace, a set of opposed pairs of contact rolls operatively positioned within said enclosure between said feed rolls and the furnace, means supplying electric energy to said contact rolls, means holding said contact rolls in flexible yieldable engagement with the electrode during its advance into the furnace, and a water-jacketed enclosure connected between said first-mentioned enclosure and the furnace and having an inner enclosing wall therealong defining an electrode passageway therethrough of substantially transversely limited extent sufficient to provide a minimum clearance between it and the electrode and to heat insulate said first-mentioned enclosure with respect to the furnace.

13. An apparatus for feeding and energizing a consumable electrode being introduced into an electric arc melting furnace which comprises, an enclosure above the furnace and defining a chamber, said enclosure being of sufficient length to contain a longitudinal length of the electrode therein, a pair of feed rolls operatively positioned within said enclosure adjacent an upper end portion thereof to engage the electrode and advance it into the furnace, yieldable contact rolls operatively positioned within a lower end portion of said enclosure to engage the electrode and supply electrical current thereto during its advance into the furnace, a heat baffling enclosure connecting the lower end portion of said first-mentioned enclosure to an upper end portion of the furnace and having means to heat insulate said first-mentioned enclosure from the furnace, said baffling enclosure having an inner wall longitudinally therealong defining an electrode passing chamber that is restricted transversely to provide a minimum clearance between said inner wall and side portions of the electrode during its advance into the furnace, a conductive base member positioned within said first-mentioned enclosure, contact roll mounting brackets pivotally mounted on said base member to extend therefrom and carry said contact rolls, and yieldable means operatively engaging said brackets to hold said contact rolls in yieldable engagement with the electrodes.

14. An apparatus for feeding and energizing a consumable electrode having four substantially planar sides that is to be introduced into an electric arc melting furnace which comprises, an enclosure above the furnace end defining a cham-

ber, said enclosure being of sufficient length to contain a longitudinal length of the electrode therein, a pair of feed rolls operatively positioned within said enclosure adjacent an upper end portion thereof to engage the electrode and advance it into the furnace, yieldable contact rolls operatively positioned within a lower end portion of said enclosure to engage the electrode and supply electrical current thereto during its advance into the furnace, a heat baffling enclosure connecting the lower end portion of said first-mentioned enclosure to an upper end portion of the furnace and having means to heat insulate said first-mentioned enclosure from the furnace, said baffling enclosure having an inner wall longitudinally therealong defining an electrode passing chamber that is restricted transversely to provide a minimum clearance between said inner wall and side portions of the electrode during its advance into the furnace, said contact rolls having two opposed pairs, one of said opposed pairs being in engagement with two of the planar sides and the other of said opposed pairs being in engagement with the other two of the planar sides of the electrode, and flexible means positioned to force said contact rolls into engagement with the planar sides of the electrode.

15. An apparatus for feeding and energizing a consumable electrode being introduced into an electric arc melting furnace which comprises, an enclosure above the furnace and defining a chamber, said enclosure being of sufficient length to contain a longitudinal length of the electrode therein, a pair of feed rolls operatively positioned within said enclosure adjacent an upper end portion thereof to engage the electrode and advance it into the furnace, yieldable contact rolls operatively positioned within a lower end portion of said enclosure to engage the electrode and supply electrical current thereto during its advance into the furnace, a heat baffling enclosure connecting the lower end portion of said first-mentioned enclosure to an upper end portion of the furnace and having means to heat insulate said first-mentioned enclosure from the furnace, said baffling enclosure having an inner wall longitudinally therealong defining an electrode passing chamber that is restricted transversely to provide a minimum clearance between said inner wall and side portions of the electrode during its advance into the furnace, pivotally mounted brackets carrying said contact rolls, and a yieldable compression spring positioned about said brackets.
